UNITED STATES PATENT OFFICE.

SAMUEL SMITH, OF MATTOON, ILLINOIS.

IMPROVEMENT IN FIRE-PROOF ROOFS.

Specification forming part of Letters Patent No. 124,767, dated March 19, 1872.

Specification describing a new and useful Improvement in Fire-Proof Roofs, invented by SAMUEL SMITH, of Mattoon, in the county of Coles and State of Illinois.

This invention relates to the construction of roofs of buildings, with a view of making them not only durable and fire-proof, but a support to the side walls of the building; and it consists in an arch, constructed as hereinafter more fully described.

In the accompanying drawing, Figure 1 is a vertical section on the line *xx* of Fig. 2, showing a roof constructed according to my invention. Fig. 2 is a top view, showing the roof and walls of the building. Fig. 3 is a vertical longitudinal section of Fig. 2 taken on the line *yy*.

Similar letters of reference indicate corresponding parts.

A A represent the side walls of a brick or stone building. B B are the end walls. C is the arch, composed of tiles D, which lock into each other, as seen in Fig. 1, laid so as to break joints with each other, as seen in Fig. 2. D' D' are bars of angle-iron laid into the wall, as seen in Fig. 1, which form the abutments of the arch. The bed-plate E of these bars extend from the wall over the joist F; and where wooden joists are used the bars may be spiked or bolted to them, which would serve to support the walls and prevent them from spreading. G represents rods of iron, which pass through the flanges H H of the abutment-bars and form chords to the arch at suitable distances from each other. These chords are protected from the action of heat in case of fire, and prevented from expanding, and consequently damaging the arch, by means of the cylindrical fire-proof tiles or composition I, placed on the chords, and secured thereto in any permanent manner. J J are the water-gutters of the roof, formed by the gutter-tiles K and L, the latter of which are laid into the walls, as seen in Fig. 1. M M are the abutment-tiles. N N are orifices in

the end walls B B, for the discharge of the water from the gutters into the conductor-pipes O O. The tiles are all laid in good cement, and the arch is formed on a temporary skeleton arch of wood, the same as in laying a brick or stone arch. When completed the arch is covered with a coating of mastic or other cement, P, so that the tile will not absorb moisture, and to render the entire roof (with the gutters) perfectly water-proof.

The side walls may be anchored to the angle-iron abutments, or to the chords, in any manner, if necessary; but as arranged in the drawing the walls would, in ordinary cases, be held together and supported in case of fire.

The chords G, being protected by the fire-proof tile or composition I, a building provided with this roof cannot be destroyed, as everything combustible inside may burn, but the roof and walls will remain.

The arch may be built on a circle of any radius, the arc simply diminishing or increasing according to the width of the building, so that tiles of the same pattern may be used for all roofs.

Having thus described my invention, I claim as new, and desire to secure by Letters Patent—

1. A roof composed of the tile-arch C, gutters J J, abutments D' D', and chords G, substantially as described.

2. The arrangement of the cylindrical fire-proof tiles with the chords G, as and for the purpose specified.

3. The abutment-tile M, as and for the purposes described.

4. The gutter-tiles K and L, in combination with the arch C and walls A A, as and for the purposes described.

SAMUEL SMITH.
